HARMON F. LUSHBAUGH AND OSCAR Z. HURD, OF MOUNT PULASKI,
ILLINOIS.

Letters Patent No. 84,291, dated November 24, 1868.

IMPROVED ANIMAL-TRAP.

The Schedule referred to in these Letters Patent and making part of the same.

To all whom it may concern:

Be it known that we, HARMON F. LUSHBAUGH and OSCAR Z. HURD, of Mount Pulaski, Logan county, State of Illinois, have invented a new and useful Improved Animal-Trap, of which the following is a full, clear, and exact description, reference being had to the annexed drawing, making a part of this specification, in which—

Figure 1 represents a longitudinal sectional elevation of my invention.

Figure 2 represents a plan of same, the cover being removed.

Figure 3 represents a detail of my invention, hereinafter described.

Similar letters indicate like parts.

It consists of a box A, figs. 1, 2, and 3, of a convenient length and height; having at the top a trap-door, a, fig. 1, one end of the box being square and covered with a grating, b, fig. 1, b, b', b'', &c., fig. 2, while the opposite end forms a semicircle, c, figs. 1 and 2, one half being enclosed by a metal sheet, d, figs. 1 and 2, while the other is left open for the door e, fig. 2.

A vertical shaft, B, figs. 1 and 2, having its bearings in the centre of the top and bottom of the end of the box, as seen in fig. 1, is made to revolve by a coil-spring, h, attached to its upper extremity, the spring being covered and protected by the cap l, fig. 1. The knob k, on the end of the shaft, operates the spring by turning the shaft.

To this shaft are fixed rods m, m', m'', &c., fig. 1, m, fig. 2, passing through it, while another rod, n, figs. 1 and 2, passes through the top of the shaft, at right angles to m, m', m'', &c., all the rods being nearly as long as the width of the box, leaving only space enough between their extremities and sides and circular end of the box for them to revolve freely.

A series of rods, o, o', o'', &c., fig. 1, o, fig. 2, curved, as shown, is attached to the side of the box, their ends falling between the rods m, m', &c.

A platform, p, of the same width as the door e, figs. 1 and 2, is pivoted at one end, while the other rests on the spring q, figs. 1 and 3, and is connected, by the link f, figs. 2 and 3, with the pawl r, fig. 3, the pawl being pivoted at s, so that the end of the rod n will engage with it, and prevent the shaft B from revolving.

To the sides of the box, at the top, is pivoted a rock-shaft, E, figs. 1 and 2, having numerous lance-heads, 1, 2, 3, 4, &c., attached to it, while a similar rock-

shaft, F, also provided with lance-heads interlacing those on E, is pivoted at the bottom of the box.

To E is attached a weight, H, figs. 1 and 2.

A platform, t, figs. 1 and 2, extending entirely across the box, is pivoted at one end at u, so as to form a continuation of the platform p, while the other extremity is supported by the link v attached to the lever w of the rock-shaft E, the rock-shaft F also being connected, by a link, x, to the lever z of the shaft E. The levers and links are seen in fig. 1, and the lever in fig. 2.

The bait being suspended at g, and the spring wound up by turning the knob k, the pawl preventing it from unwinding, the trap is ready for use. A rat having passed well on to the platform p, depresses it, disengaging the pawl r, and allowing the shaft to revolve, the rods m, m', m'', &c., strike him and push him into the trap. The rods o, o', &c., and m, m', &c., preventing the rat from retreating, he passes on to the platform t, which falling, by means of the links and levers, opens the lance-points, allowing him to pass through, the lances immediately, by the action of the weight H, resuming the position shown in fig. 1 effectually preventing the rat from returning. When the pawl is disengaged, the shaft makes a half revolution till the other end of the rod, engaging with the pawl, sets the trap again. The rats may be taken out through the trap-door, or the grating may be made movable for this purpose.

The trap being once set, will continue to act till the spring is unwound or the box is filled.

What I claim as my invention, and desire to secure by Letters Patent, is—

1. The combination of the shaft B, coil-spring h, rods m, m', m'', m', o, and n, n', n'', n'', platform p, with its springs q, link f, and pawl r, as and for the purpose specified.

2. The combination of the platform t, links v and x, levers w and z, rock-shafts E and F, with their lance-heads and weight, as and for the purpose specified.

3. An animal-trap, formed by the combination of the parts hereinbefore described, as and for the purpose specified.

HARMON F. LUSHBAUGH.
OSCAR Z. HURD.
